UNITED STATES PATENT OFFICE.

ALFRED J. THIBAULT AND RAOUL R. THIBAULT, OF CLAREMONT, NEW HAMPSHIRE.

SPADE.

Application filed August 12, 1922. Serial No. 551,420.

To all whom it may concern:

Be it known that we, ALFRED J. THIBAULT and RAOUL R. THIBAULT, citizens of the United States, residing at Claremont, in the county of Sullivan and State of New Hampshire, have invented new and useful Improvements in Spades, of which the following is a specification.

This invention has for its chief object, the provision of an automobile accessory, in the nature of a spade or the like made up of a plurality of parts, which are designed to permit them to be easily assembled or disassembled as the occasion may require, the spade possessing maximum strength and rigidity for use, while the construction is such that the parts when disassembled can be conveniently arranged in the tool box of the machine.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:

Figure 1 is a view in elevation of the spade constructed in accordance with the invention.

Figure 2 is a view, shewing the blade sections arranged in operative relation but separated from the handle.

Figure 3 is a sectional view taken on line 3-3 of Figure 1.

Figure 4 is a detail view of the handle.

Figure 5 is a view in elevation of the reinforcing plate.

Figure 6 is an edge elevation of the reinforcing plate.

Referring to the drawings in detail, 10 indicates the handle of the spade which may be constructed from any suitable material and vary in cross sectional configuration without departing from the spirit of the invention. The lower end of this handle supports what we term a lock plate 11, and which plate is provided with a curved slot 12, which extends from a point at one side of the longitudinal center of the plate and opens at one side thereof. The blade is made up of two sections indicated at 14 and 15 respectively, and these sections are iden-

tical in construction. Each section is provided with spaced openings 16 and 17 respectively, and which openings are arranged adjacent the upper and lower ends 60 of the blade. The meeting edges of these sections are cut away as at 18 and 19, the cut away portions 18 of the respective sections unitedly defining a circular opening, while the corresponding cut away portions 65 19 unitedly define an oblong opening, when the sections of the blade are associated.

In conjunction with the parts above described, we also make use of a reinforcing plate indicated at 20, and this plate being of an elongated contour, and arranged to bridge the meeting edges of the blade sections. One end of this plate 20 is formed to provide an upturned portion 21, which is slightly spaced from the body portion 20 of the plate and together therewith defining what we call the toe portion of the reinforcing plate. This portion is designed to provide a reasonably sharp edge 22, to facilitate use of the tool in its entirety. Manifestly, this reinforcing plate is slightly longer than the blade, and terminates at its outer end to provide an extension 23 which bears against the adjacent side of the handle 10. Projecting from one side of the plate 20 are spaced pairs of lugs, one pair of these lugs being indicated at 24 and adapted to be received by the corresponding openings 16 of the respective sections of the blade, while the other pair of lugs are indicated at 25 and adapted to be received by the corresponding openings 17 of the blade sections. Also projecting from the plate 20 is a lug 26, designed to accommodate itself within the opening defined by the cut away portions 18 of the blade sections. The plate 20 is also provided with an oblong opening adapted to register with the like opening defined by the entrance portions 19 of the blade sections above referred to. A lug 27 100 carried by the plate 11 is received by these openings as illustrated.

It will be noted that the cut-away portions 19 are such, that when the blade sections are associated, that the opening defined by said cut-away portions has its opposed edges curved as at 28. The lug 27 is provided with projecting portions 27' which are adapted to be received by these curved portions of the opening to assist in holding the parts operatively associated. It will be further noted that the lug 26 is provided at one

side with projections 26' adapted to be received by the depressions 13 provided in the lock plate 11.

As hereinabove stated, this tool is primarily intended as an automobile accessory, as the use of such tools is frequently desired by tourists, for the purpose of removing mud, snow and the like from about the wheels of the vehicle when the latter is stalled or stuck in mud or snow which frequently happens. It is also useful in digging post holes for tents and trenches about a tent, and as a matter of fact has any number of uses as an automobile accessory.

Manifestly, the component parts of the tool can be easily and quickly disassembled and the parts arranged in the tool box of the vehicle, and can also be very quickly assembled when its use is desired. To assemble the tool, it is only necessary to arrange either one of the blade sections on the reinforcing plate 20, the openings 16 and 17 of said sections receiving the adjacent lugs 24 and 25. The other section of the blade is then associated with the reinforcing plate 20, the lug 26 being received by the opening 18 and the lug 27 of the plate 11 being received by opening 19 of the blade section. The handle 10 is then arranged at an angle to the blade, as for instance, approximately ninety degrees, in order to position the open end of the slot 12 with relation to the lug 26, so that when the handle 10 is swung or moved to a true vertical position, this lug 26 will be positioned at the closed end of the slot, and the projections 26' arranged within the depressions 13 of the plate 11. The component parts are in this manner held fixed relatively in position for use, with no possibility of the parts being casually separated or deranged incident to the use of the tool. It will be noted that the lower end portions of the blade sections are cut away as at 30 to receive the toe portion of the reinforcing plate, and this portion is made particularly strong, inasmuch as it is subjected to the most use and wear.

While it is believed that from the foregoing description, the nature and advantages of the invention will be readily apparent, we desire to have it understood that we do not limit ourselves to what is herein shown and described, and that such changes may be resorted to when desired as fall within the scope of what is claimed.

What we claim is:-

1. A tool of the character described comprising a handle, a lock plate at one end thereof, a blade including two sections

adapted to be arranged edge to edge, said sections having spaced openings, a reinforcing plate arranged at one side of the blade bridging the meeting edges thereof, lugs projecting from said reinforcing plate and passing through the openings of said blade, and said locking plate having a slot adapted to receive one of said lugs at the opposite side of the blade for the purpose specified.

2. A tool of the character described comprising a blade made up of two sections arranged in edge to edge relation, said sections having spaced openings, and cut-away portions unitedly defining openings, a handle, a lock plate depending from the handle and adapted to be arranged at one side of the blade sections and extended beyond the meeting edges thereof, a reinforcing plate arranged at the opposite side of the blade sections and having an up-turned portion receiving the lower edges of the blade sections, lugs projecting from the reinforcing plate, said lugs corresponding to the configuration of said openings and passed through the latter, said locking plate having an arcuate-shaped slot, and one of said lugs being received by said slot, incident to the association of the handle with the blade as described.

3. A tool of the character described comprising a blade made up of two sections arranged edge to edge, said sections having spaced openings, and cut-away portions unitedly defining openings, a handle, a lock plate depending from the handle and arranged at one side of the blade sections, said plate having an arcuate-shaped slot opening at one side of the plate, and depressions arranged above and below said slot adjacent the closed end thereof, a reinforcing plate having an upturned extremity defining a toe portion adapted to receive the corresponding lower edges of the blade sections, an extension projecting from the other end of the reinforcing plate and arranged to bear against the handle, lugs projecting from the reinforcing plate and adapted to be received by said openings, and one of said lugs being received by the slot of the lock plate incident to the association of the handle with said blade, and projections formed on the latter mentioned lug and adapted to be received by the depressions of said lock plate for the purpose specified.

In testimony whereof we affix our signatures.

ALFRED J. THIBAULT.
RAOUL R. THIBAULT.
